UNITED STATES PATENT OFFICE

2,478,095

DEVICE FOR MAKING THE POINTS OF
COLLARS, CUFFS, AND THE LIKEGeorges Germain, Romorantin, France; vested in
the Attorney General of the United StatesApplication December 30, 1942, Serial No. 470,622
In France January 23, 1941Section 1, Public Law 690, August 8, 1946
Patent expires January 23, 1961

4 Claims. (Cl. 223—42)

1

The present invention has for an object a device for the mass production of the points of collars, the device allowing a rapid and sure production by a simple operation effected by the worker consisting in turning out and forming the point.

It is known that the collar being stitched, that is to say the two strips of fabric of the collar and the stiffening having been assembled by a line of stitching effected on the wrong side of the fabric, it must be turned out on to the right side. For that purpose, use has been made of devices having piercers, with which the collar is nipped before turning it inside out. Said devices have, however, various inconveniences which are remedied by the device according to the present invention.

In the pocket formed by the two strips of fabric forming the point of the collar, nippers are introduced which terminate in two thin and pointed noses. One at least of said noses is held spaced from the other, and means are provided so that, when the noses are engaged up to the bottom of the pocket, the noses can slightly nip the extreme point of the collar which has been previously slightly engaged between them. It suffices at this instant, to turn the pocket inside out, then to loosen the noses for the collar to be correctly turned inside out and ready to be finished.

A device will be described hereinafter allowing to effect this nipping of the point of the collar and turning it out in the minimum of time and by a simple operation.

In the accompanying drawing:

Fig. 1 is an elevation of the device, partly in section.

Fig. 2 is a horizontal section of the nippers according to line II—II of Fig. 1.

Fig. 3 is a similar view of the nippers in closed position.

Fig. 4 is a top plan view of the device.

The device comprises a hollow frame 1 of angular form; the horizontal portion 2 of which is provided at the desired height for working and in which are secured the nippers 3; said nippers comprise a fixed nose 4 and a nose 5 movable about a fixed pin 6; the portion 17 of nose 5 located behind said pin is provided with a notch 16 forming two rolling inclines for a roller 7 mounted at the end of a rod 8. Said rod is pivoted at 10 on one of the arms of the right angle member 9, the other arm of which is pivoted at 11 to a vertical rod 12 connected to a control lever or pedal, not shown in the

2

drawing. Said right angle member 9 is loosely mounted on a spindle 13 secured to the frame 1. A returning spring 14 is mounted between an abutment 15 adjustable on the rod 8 and the nippers 3.

The operation of this device is as follows: In position of rest, the spring 14 pulls the rod 8 in the direction opposed to the noses; consequently, the roller 7 rolls towards the bottom of the notch 16, rocking the member 17 in a clockwise direction, which has for effect to move the movable nose 5 away from the fixed nose 4.

At this moment the worker fits over said noses the pocket 18 (illustrated in dot and dash lines in Fig. 2) formed by the two thicknesses 19, 20 of the fabric of the point of the collar and the stiffening 21, all three assembled by a line of stitching; when the point of the collar is completely fitted over the nippers 3 (position shown in the drawing), it suffices to engage about 1 or 2 m.m. of the fabric at the extreme point of the collar between the noses 4 and 5 which are spaced apart. At this moment the worker operates the control lever or pedal; the bell crank lever 9 pushes the rod 8 forwardly; the roller 7 rolls on the inclines of the notch 16, which has for effect to rock the portion 17 of the movable nippers about the pin 6 in a counter-clockwise direction to clamp the nose 5 against the nose 4. The point of the collar is therefore firmly gripped between the noses of the nippers, as long as the worker actuates the control; it suffices for the latter to grip the pocket 18 and to pull it backwardly for turning the collar inside out. At the end of this operation, the worker ceases to actuate the bell crank lever and the collar is released, the part of the fabric gripped between the noses 4 and 5 forming the point of the collar.

Of course certain details of this device, such as the control of the movable nose, the assemblage of the movable nose or noses, etc. may be modified without departing from the scope of the invention.

The invention is naturally applicable to all kinds of collars, cuffs, wrist-bands, etc., it allows the work to be effected rapidly and surely without any risk of deteriorating the articles, the finishing of the points of which is perfect.

I claim:

1. In a device for turning out the points of collars, cuffs and other lingerie articles, the combination of a tapered cone-shaped support, nippers having pointed noses at one end of said support and forming the apex of said cone when the noses are in closed position, one of the noses of

said nippers being rigid with said cone and the other being pivotally mounted on said cone and provided with an extension on which is formed a slotted cam, a hollow L-shaped goose-neck, one leg of said goose-neck being secured to the base of said cone-shaped support, a control rod within said cone and said hollow goose-neck, means for moving said rod longitudinally, a roller at one end of said rod, and means for causing said roller to cooperate with said cam slot.

2. In a device for turning out the points of collars, cuffs and other lingerie articles, the combination of a tapered cone-shaped support, nippers having pointed noses at one end of said support and forming the apex of said cone when the noses are in closed position, one of the noses of said nippers being rigid with said cone and the other being pivotally mounted on said cone and provided with an extension on which is formed a slotted cam, a hollow L-shaped goose-neck, one leg of said goose-neck being secured to the base of said cone-shaped support, a control rod slidably mounted in the base of said cone-shaped support and projecting into the adjacent hollow leg of said goose-neck, a bell crank mounted in said goose-neck substantially at the point of bending, one leg of said bell crank being pivotally secured to said rod, an operating link connected to the other leg of said bell crank, said link projecting through the other hollow leg of said goose-neck, a roller at one end of said rod, and means for causing said roller to cooperate with said cam slot.

3. In a device for turning flexible laminated angle-shaped articles having the converging marginal edges thereof secured together by seam lines converging at a point, the combination of a tapered cone support adapted to be inserted intermediate said laminations and between said converging seam lines, nippers carried by one end of said support, said nippers having pointed noses for gripping the article substantially at said point, said noses forming the apex of said cone

when the noses are in closed position, a hollow bracket joined to the base of said cone-shaped support, and operating means disposed within said hollow bracket and connected to said nippers for opening and closing the latter.

4. In a device for turning flexible laminated angle-shaped articles having two adjacent marginal edges thereof secured together, thereby forming an angle-shaped pocket between the laminations, the combination of a tapered cone-shaped support adapted to be inserted intermediate said laminations and between said secured edges, nippers carried by one end of said support, said nippers having pointed noses for gripping the article at the corner of said pocket, said noses forming the apex of said cone when the noses are in closed position, a hollow bracket joined to the base of said cone-shaped support, the periphery of said bracket being flush with the base of said support at the junction point, and operating means disposed within said hollow bracket and connected to said nippers for opening and closing the latter.
